UNITED STATES PATENT OFFICE.

SIDNEY A. KELLER, OF NEW YORK, N. Y., ASSIGNOR TO LONG & KOCH
OF NEWARK, NEW JERSEY, A CORPORATION OF NEW JERSEY.

DESIGN FOR A BACK FOR BRUSHES, MIRRORS, OR SIMILAR ARTICLES.

SPECIFICATION forming part of Design No. 35,891, dated May 6, 1902.

Application filed March 12, 1902. Serial No. 97,954. Term of patent 3½ years.

To all whom it may concern:

Be it known that I, SIDNEY A. KELLER, a citizen of the United States, residing at New York, borough of Manhattan, county of New York, and State of New York, have invented and produced a new and original Design for a Back for Brushes, Mirrors, or Similar Articles, of which the following is a specification, reference being had to the accompanying drawing, which shows in elevation a brush or mirror back having my newly-invented design applied thereto.

As shown in the drawing, the leading features of my design consist of the floral decoration at the upper end of the back, representing tulips, below which is the head of a female figure, the extreme lower end of the handle itself being in the form of a tulip, all being in relief.

Referring to the drawing, A represents the back proper, and B the handle, the upper end of the back being decorated with the tulips C C, the stem and leaves D D forming a border which merges into the scroll E at the junction of the handle and back. Above the scroll is the head of a female figure F, the lower extreme end of the handle itself having the form of a tulip G.

What I claim is—

The design for a back for brushes, mirrors or similar articles, substantially as herein shown and described.

SIDNEY A. KELLER.
